Des. 178,270
Patented July 17, 1956

178,270

PARLOR MILKING STALL

Henry B. Babson, Chicago, Ill., assignor to Babson Bros.
Co., a corporation of Illinois

Application November 14, 1955, Serial No. 38,864

Term of patent 14 years

(Cl. D23—1)

Fig. 3.

The broken line structure representing the platform and partition is depicted for illustrative purposes only.

I claim:

The ornamental design for a parlor milking stall, as shown and described.
